בְּתִירָא

UNITED STATES PATENT OFFICE.

ROBERT KENNETH MILKS, OF OTTAWA, ONTARIO, CANADA.

BAG-HOLDER.

1,121,388.

specification of Letters Patent. Patented Dec. 15, 1914.

Application filed December 6, 1913. Serial No. 805,054.

To all whom it may concern.

Be it known that I, ROBERT KENNETH MILKS, a subject of the King of Great Britain, and resident of the city of Ottawa, 5 Province of Ontario, Dominion of Canada, have invented certain new and useful Improvements in Bag-Holders, of which the following is a specification.

My invention relates to bag holders for 10 garbage collectors and particularly refers to that type of collector utilized in kitchens and like places, and the objects of my invention are to render the collected garbage more easily removed and destroyed, to keep 15 the surrounding places in which such a collector is fixed in a dry and sanitary state, and to generally overcome the disagreeable conditions usually associated with garbage collectors.

20 Specific objects of the invention are to enable the various parts to be readily assembled or taken apart, and to simplify and improve the mechanical construction, and it consists essentially of a suitable stand having detachable means at the top and bottom 25 for supporting the collecting bag, with the mouth thereof open, and a cover hinged to the stand, the parts being arranged and constructed in detail as hereinafter more particularly described in the following specification.

Figure 1 is a perspective view of my device. Fig. 2 is a side elevation partly sectional of the same. Fig. 3 is a perspective 35 view of the supporting hoop.

Like letters of reference refer to like parts in the several drawings.

Referring to the drawings, A represents the bracket or stand comprising a back or 40 wall plate 1 consisting of the flanged parts 2 and the rectangular projecting part 3 extending therefrom, such flanges and projecting part extending the whole length of the back plate in a vertical direction. This 45 back plate is provided with orifices 4 extending through the flanges 3 and with spaced slots 5 extending in and transversely across the front face of the said rectangular projecting part 3, the said orifices being 50 designed to engage with screws or nails whereby the bracket is fixed in any desired position to any suitable support.

6 represents a supporting bracket or base 55 consisting of the top plate 7 and the flanges 8 formed integral with such top plate, the back of the said bracket being formed with

an upwardly turned tongue 9 substantially at right angles to the said top plate 7, such tongue being adapted to engage with the slots 5, the bracket being formed on the 60 under side with an abutment 9^a adapted to engage the face of the back or wall plate and maintain the bracket in substantially horizontal position.

10 represents the supporting hoop consisting of the flanged ring 11 having the bracket 12 attached thereto, such bracket being provided with an upwardly extending tongue 27 designed to engage with the uppermost slot 5, the bracket having an abutment 27^a 70 engaging the face of the back or wall plate adapted to maintain the bracket in substantially horizontal position. The hoop is further provided with bands 13 and 14 pivotally attached to the bracket 12 by means 75 of the bolts 15, such bands being designed to extend around the outer periphery of the hoop 10 and be held in engagement therewith by the pin 15' extending from the front of the band 13 and engaging with the 80 orifice 16 in the band 14.

17 represents a lid of any suitable shape supported from the stand and adapted to cover the hoop 10, such lid being conveniently provided with a hinge plate 18 pivotally attached to the front face of the rectangular projecting part 3 by means of the pin 19 engaging with the jaws 20 suitably attached to the said front face.

B represents a bag of any suitable material, that preferably used being of oiled paper, such bag being designed to be supported from the hoop 10 and to be held in engagement therewith by means of the bands 13 and 14.

95 Having described my invention I will now show the manner in which it is assembled: The back plate 1 is attached to any suitable support by means of screws engaging with the orifices 4 in the flanges 2, 100 the height of such bracket being determined by its convenience to the user. The tongue 27 of the bracket 12 is now engaged with the slot 5 whereupon the hoop 10 takes up a position at right angles to the back plate 1. 105 The supporting bracket 6 is similarly attached to the base of the back plate by means of the tongue 9 engaging with the slot 5. The bands 13 and 14 are now opened and the mouth of the bag B is placed over 110 the flanged part of the hoop 10, the bands being then closed to hold the bag in en-

gagement therewith. As the bags are made in several lengths the bracket 6 can be adjusted by elevating or lowering it to any one of the slots located in the front face of the bracket 1. The cover or lid 17 is pivotally attached to the jaws 20, but it is not desirable to remove such lid at any time as the hinged plate is so set back that when the lid is open it is not capable of being closed, 10 unless the operator desires that it should do so.

When the bag B is full of the collected garbage it is removed by opening the bands 13 and 14, the bag being finally closed by 15 means of the cord 21 extending around the top thereof, such cord being held in position by means of the retaining strips 22 attached to the said bag.

It will be observed that the arms 13 and 20 14 form a simple and effective means of clamping the bag in position. When the arms are overlapped, they will directly and automatically interlock, the pin 15 slipping into the orifice 16 as already explained.

25 As many changes could be made in the above construction and many apparently widely different embodiments of my invention, within the scope of the claims, constructed without departing from the spirit 30 or scope thereof, it is intended that all matter contained in the accompanying specification and drawings shall be interpreted as illustrative and not in a limiting sense.

What I claim as my invention is:

35 1. A bag holder comprising a back plate adapted to be secured to a support formed with flanges having orifices therein and a rectangular projecting part extending from

said flanges and formed integral therewith, such projecting part having slots therein 40 and extending transversely across the front face thereof, and a bag supporting means adapted to engage in the said slots.

2. A bag holder comprising a back plate and bag holding means mounted thereon and consisting of a ring and a pair of clamping arms movable to clamp a bag around the ring, said arms having overlapping free ends adapted to directly and automatically interlock. 50

3. A bag holder comprising a back plate formed with a vertically recessed central projecting part having slots extending transversely across the face and side flanges with orifices, a bag, and holding means for the top and bottom of the bag adapted to engage in said slots. 55

4. A bag holder comprising a back plate formed with a vertically recessed central portion having a series of transverse slots, 60 a bracket for holding the top of the bag having one tongue adapted to extend through one of the slots and another tongue adapted to bear against the face of the plate and bag supporting means for the bottom 65 of the bag also having a tongue adapted to extend through one of the slots and a second tongue adapted to bear against the face of the back plate.

In witness whereof I have hereunto set 70 my hand in the presence of two witnesses.

ROBERT KENNETH MILKS.
